UNITED STATES PATENT OFFICE.

KARL W. MOORE, OF CYNTHIANA, KENTUCKY.

TAIL-DOCKING MACHINE.

Application filed February 3, 1926. Serial No. 85,743.

This invention relates to improvements in machines for docking the tails of lambs and has as one of its objects to provide a machine for this purpose which may be readily and quickly operated to sever the tails with a clean cut so that the stumps will rapidly heal and so that the operation will be less painful than when performed by the ordinary machines for this purpose.

5 Another object of the invention is to provide a docking machine in which the cutting blade is so mounted and operated as to effect a shear cut as distinguished from a chopping cut.

10 Another object of the invention is to provide means whereby the blade will be normally yieldably supported in inactive position so that the operator of the machine may conveniently position the lamb with respect to the machine, having the free use 20 of both hands and not being required to hold the blade elevated.

Another object of the invention is to provide means whereby the blade will be automatically supplied with an antiseptic at each operation of the blade so that antiseptic will be applied to the stub of the tail at the time the tail is docked, thereby obviating the necessity of applying such a 30 medicament subsequent to the docking operation.

Another object of the invention is to provide a docking machine which may be manufactured at an extremely low cost and which will be simple in construction and not liable to any disarrangement of its component parts.

In the accompanying drawings:

Figure 1 is a view in side elevation of the 40 docking machine embodying the invention, parts being broken away and parts being shown in section, the blade of the machine being shown in full lines in elevated or inactive position and in dotted lines in lowered or cutting position.

Figure 2 is a vertical transverse sectional view taken substantially on the line 2-2 of Figure 1, looking in the direction indicated by the arrows.

50 Figure 3 is a horizontal sectional view taken substantially on the line 3-3 of Figure 1, with the blade in lowered position.

Figure 4 is a vertical transverse sectional view taken substantially on the line 4-4 of Figure 3, looking in the direction indicated by the arrows.

Figure 5 is a fragmentary sectional perspective view illustrating in detail the means provided for yieldably supporting the blade in elevated position.

The machine embodying the invention comprises two side plates which are indicated by the numeral 1 and which are provided at their rear ends with right angularly extending flanges 2 constituting attaching means, screws 3 being fitted through openings in the said flanges and driven into a post, the side of a barn, or any other convenient fixed object. The lower edge portions of the plates 1 are bent to extend laterally at right angles in opposite directions as indicated by the numeral 4, and these portions 4 are bent back upon themselves to provide flanges 5 which serve to not only reinforce the portions 4 but also to engage and support lateral flanges 6 at the upper edges of the side walls 7 of a disinfectant or antiseptic tank, which is indicated by the numeral 8 and into which any suitable disinfectant or antiseptic may be introduced. The rear edges of the plates 1, indicated by the numeral 9, are extended on downwardly and forwardly inclined lines and are, therefore, disposed in an inclined position above the lower edge portions 4 of the plates at the rear of the machine and are spaced above the plane of the said portions 4 so that the tails of the animals to be docked may be disposed between these edge portions and in position resting upon the said portion 4. 90 Rearwardly of the rear edges 9 of the plates 1, their edge portions 4 are spaced apart to provide a slot which is indicated by the numeral 10 and which extends longitudinally above the tank 8, and it will be understood that the plates may constitute an integral structure including their said edge portions 4, as shown in Figure 3, or their said edge portions 4 may be suitably bridged and connected at the rear end of the structure.

It will be observed by reference to Figures 1, 3 and 4 of the drawings that due to the downward and forward inclination of the edges 9 of the plates 1, the walls of the slot 10 are constituted by the inner or opposing edges of the edge portions 4 so that one of these walls, indicated by the numeral 11, constitutes a shearing edge with which the blade of the machine coacts in a manner to be presently explained.

The blade, which is indicated in general

by the numeral 12, is riveted or otherwise secured at its upper edge portion to an arm 13 provided at its rear end with a handle 14 and pivotally connected at its forward end by a pivot pin 15, to the lower ends of spaced links 16 which are, in turn, suspended for swinging movement from a pivot bolt 17 secured through the side plates 1 of the machine, washers 18 being arranged upon the said bolt 17 to suitably space the links 16 with relation to each other and likewise with relation to the side plates 1. The side plates 1 are formed with downwardly and forwardly inclined slots 19 which are located opposite each other and extend substantially parallel to the edges 9 of the said plates, and the lower wall of each slot is provided with an outstanding flange indicated by the numeral 20. A pin 21 is secured transversely through the arm 13 and the forward end of the blade 12 and works in the said slot 19, the ends of the said pin 21 projecting a sufficient distance beyond the opposite sides of the said arm 25 and blade to project through the slots and ride upon the flanges 20. The blade is beveled along its lower edge portion to provide an arcuate cutting edge which is indicated by the numeral 22. The opposite side 30 of the blade is plane so that the cutting edge 22 may have shearing coaction with the edge 11 heretofore referred to and which edge constitutes one wall of the slot 10, it being understood that due to the curvilinear 35 shape of the cutting edge of the blade and its shearing coaction with the edge 11, the tail disposed upon the members 4 and between the said members and the edges 9 of the plates 1, will be cleanly severed and particularly due to the fact that the blade has a floating movement inasmuch as it is supported by the links 16 and guided in its travel by the projecting ends of the pin 21 which ride along the flanges 20. It will be 40 observed by reference to Figures 1 and 4 of the drawings that when the blade-carrying arm 13 is moved downwardly, the blade will follow a downward and forward arcuate path and, in its full lowered position, will be substantially immersed in the antiseptic which is contained within the tank 8 and, when the blade carrying arm is swung upwardly and rearwardly, the blade will carry with it some of the antiseptic which will be applied to the butt or stub of the animal's 45 tail at the next docking operation.

In order that the blade may be yieldably sustained in an elevated position, a resilient detent finger 23 is secured at one end to the 50 upper end of one of the flanges 20 and extends downwardly and forwardly and is provided with a bend forming a nose 24 behind which the projecting end of the pin 21 may engage in the manner shown in Figure 1 of the drawings, so as to retain the

blade in an elevated position while the tail is being positioned upon the members 4 and beneath the edges 9 of the side plates. The finger 23 is located at the upper end of the slot 19 beside which it is positioned and it will be understood that due to the resiliency of the said finger, but little resistance will be offered to downward movement of the blade-carrying arm 13 in the operation of the machine. 75

Having thus described the invention, what I claim is:

1. In a tail docking machine, a support constituting a stationary rest for the tail to be docked, and a cutting blade supported for 80 slidable movement in a curvilinear path toward and from the rest and coacting therewith when moved in the direction of the rest to impart a shearing cut to the tail thereon. 85

2. In a tail docking machine, spaced supporting plates, a link suspended for swinging movement between the said plates, an arm pivotally connected at one end with the lower end of the said link, a blade carried by the said arm, the said plates having inclined slots formed therein, a support constituting a rest for the tail to be docked, and a pin carried by the arm and engaging at its ends in the said slots whereby to effect 95 guiding of the blade in a curvilinear path toward and from the said support. 90

3. In a tail docking machine, spaced supporting plates, a link suspended for swinging movement between the said plates, an arm pivotally connected at its lower end with the link, the plates having inclined slots therein, a pin carried by the arm and engaging at its ends in the said slots, a blade carried by the arm, a handle at the 100 outer end of the arm, and a support constituting a rest for the tail to be docked and positioned in the path of movement of the said blade. 105

4. In a tail docking machine, spaced supporting plates, a link suspended for swinging movement between the said plates, an arm pivotally connected at one end to the said link, the plates having inclined slots therein, flanges extending laterally outwardly from the lower walls of the slots, a pin carried by the arm and having its end portions projecting into the slots and riding upon the said flanges, a blade carried by the arm, a handle at the outer end of the arm, 115 and a support constituting a rest for the tail to be docked and positioned in the path of movement of the said blade. 120

5. In a tail docking machine, spaced supporting plates, a link suspended for swinging movement between the said plates, an arm pivotally connected at one end to the said link, the plates having inclined slots therein, flanges extending laterally outwardly from the lower walls of the slots, a pin 130

- carried by the arm and having its end portions projecting into the slots and riding upon the said flanges, a blade carried by the arm, a handle at the outer end of the arm, 5 and a support constituting a rest for the tail to be docked and positioned in the path of movement of the said blade, the said support having an edge portion for shearing contact by the cutting edge of the blade.
- 10 6. In a tail docking machine, a support constituting a rest for the tail to be docked, a container arranged below the support for containing an antiseptic, and a blade mounted for movement toward and from the said 15 support and, entering the said container, when moved in the direction of the support.
7. In a tail docking machine, a support constituting a rest for the tail to be docked and having a slot therein one wall of which 20 constitutes a shearing edge, a container mounted beneath the support and open at its top and communicating with the said slot, and a blade mounted for movement
- toward and from the support and having a cutting edge for shearing coaction with the 25 said shearing edge of the support, the blade entering the said container in its movement toward the support.
8. In a tail docking machine, spaced supporting plates, a link suspended for swing- 30 ing movement between the plates, the plates having inclined slots therein, an arm pivotally connected at one end to the link and moving between the said plates, a pin carried by the arm and having its end portions projecting into the slots, means upon one of the plates for engagement with one end of the pin when the arm is in elevated position to yieldably support the said arm in such position, a blade carried by the arm, and a sup- 35 port constituting a rest for the tail to be docked and located in the path of movement of the said blade.

In testimony whereof I affix my signature.

KARL W. MOORE.
